(57) CLAIM

The ornamental design for a tube display package, as shown and described.

DESCRIPTION

FIG. 1 is a front view of the tube display package showing our new design;

FIG. 2 is a rear view thereof;

FIG. 3 is a right side view thereof;

FIG. 4 is a left view thereof;

FIG. 5 is a top view thereof;

FIG. 6 is a bottom view thereof; and,

FIG. 7 is a perspective view thereof. The broken lines shown in FIG. 7 are for illustrative purposes only and form no part of the claimed invention.
